UNITED STATES PATENT OFFICE.

HARRY M. NEER, OF COLUMBUS, OHIO, ASSIGNOR TO THE TURNBULL MANUFACTURING COMPANY, OF COLUMBUS, OHIO, A CORPORATION OF OHIO.

VALVE-GRINDER.

1,161,070.

Specification of Letters Patent. Patented Nov. 23, 1915.

Application filed May 8, 1915. Serial No. 26,372.

To all whom it may concern:

Be it known that I, HARRY M. NEER, a citizen of the United States, residing at Columbus, in the county of Franklin and State 5 of Ohio, have invented certain new and useful Improvements in Valve-Grinders, of which the following is a specification.

My invention relates to valve grinders adapted to manipulate the valves of an internal combustion engine in such manner 10 that a perfect contact between the valve head and its seat may be gotten. As is customary, these valves are given a rotary motion when a suitable grinding compound has 15 been placed between their heads and the valve seat.

However, the main object of my invention resides in providing a type of structure wherein the valve head is given an oscillatory movement of a nature so that it will 20 not seat itself each time in identical positions in order to avoid the grinding of ridges and the like.

A still further object of my invention resides in the provision of a structure whereby 25 the valve head may be rotated or oscillated first in one direction and then in the other, the circular length of successive rotations being different in order to avoid the possibility 30 of the valve seating itself in identical positions during successive rotations. In this connection, it is also an object of the present invention to provide a structure for accomplishing the above by a continuous operation 35 of the driving means in the same direction.

Still a further object of my invention resides in the provision of a peculiar type of 40 bevel gear designed to mesh with complementary pinions for accomplishing the results above outlined.

The preferred embodiment of my invention 45 is shown in the accompanying sheet of drawings, in which similar characters of reference designate corresponding parts, and

50 in which:

Figure 1 is a central vertical section of my grinding tool, Fig. 2 is a side elevation of the structure shown in Fig. 1 and looking from the right, and, Fig. 3 is a face view

55 of a bevel gear used by me.

In these several figures, there is shown an upstanding shaft designated 1, this shaft being enlarged at its lower end as shown at 2 and bifurcated to receive a suitable type

position by means of the pin 4. This shaft is journaled in a suitable supporting structure or housing composed of a major section 5 and a cap 6, the major portion 5 being provided with a suitable bearing 7 adjacent its 60 underside, while its upper side is socketed as is shown at 8 to form a bearing place for this shaft 1. The upper portion of the supporting or housing structure is also provided with a hand grip of the nature shown 65 at 9, it being intended that the grinder as a whole shall be held in position by one hand of the operator, so that the bit 3 may be in operative engagement with the valve head, while the other hand is free for use as will 70 be presently related. Reference to Fig. 1 will also disclose that the shaft 1 rigidly carries a pair of bevel pinions 10 and 11, these pinions being rigidly held in position by means of pins 12 and being of slightly 75 varying diameters. A lateral portion of the major portion 5 of the housing structure is also provided with a bearing hub such as is shown at 13, through which the shaft 14 80 rotatably passes. At its outer end, the shaft carries a collar 15 to which a hand operating crank 16 is rigidly attached while its inner end rigidly carries a bevel gear designated generally by the reference numeral 17 by means of the pin shown at 18. Reference 85 to Fig. 3 will show this bevel gear in detail and from an inspection of this figure, it will be noted that it is segmental in nature and carries two sets of teeth, it being intended that each bevel pinion 10 and 11 90 shall have its own set of teeth with which it meshes. These teeth are divided into sets by making the major portion of them or those designated 19 of a length equal to approximately two times the face of each of the 95 pinions 10 and 11 and in addition to these, two small teeth 20 are provided one at each end of the circular array of teeth 19, these latter teeth 20 having a face length equal to the face of the teeth on the pinion 10 100 only. Again referring to Fig. 1, it will be noted that the arrangement of pinions 10 and 11 is such that the teeth on the pinion 10 mesh with the teeth on the outer periphery of the gear 17, while the teeth on the 105 pinion 11 mesh with the teeth on the inner periphery of the gear 17. Consequently, during the continued rotation of the operating shaft 14, the pinion 10 will mesh with all of the teeth 19 plus the two teeth 20, 110

while the pinion 11 will mesh with only the teeth designated 19, thereby giving the shaft 1 an additional rotation equal to the distance of the two teeth 20 when the pinion 5 10 is in mesh than when the pinion 11 is in mesh. It will also be noted that these teeth 19 and 20 cover an arc slightly less than half the circumference of the gear 16, whereby the valve head may be given sufficient 10 time to come to an actual stop before its rotation in the opposite direction without the accompaniment of a shock.

From the foregoing description taken in connection with the accompanying drawing, 15 it will be apparent that I have provided a type of valve grinding tool wherein the valve head may be given a circular movement first in one direction and then in the other by a continuous rotation of the operating crank 16. At the same time, the circular length of rotation in opposite directions is of unequal lengths whereby the valve head will not come to rest successively in identical positions and in this manner the 20 25 grinding of ridges, etc., is avoided.

What I claim, is:

1. In a valve grinder, an upstanding shaft, a supporting structure therefor, a bit carried by said shaft, a pair of bevel pinions 30 carried by said shaft, and a bevel gear arranged to mesh with said pinions, said gear being provided with a set of teeth for each

pinion and one set being greater in number than the other set whereby said shaft is rotated first in one direction and then in the other, the arcs of rotation being of different 35 circular lengths.

2. In a valve grinder, an upstanding shaft, a supporting structure therefor, a bit carried by said shaft, a pair of bevel pinions 40 carried by said shaft, and a bevel gear arranged to mesh with said pinions, said gear being provided with a set of teeth for each pinion whereby said shaft is rotated first in one direction and then in the other.

3. In a valve grinder, an upstanding shaft, a supporting structure therefor, a bit carried by said shaft, a pair of bevel pinions of different diameters carried by said shaft, and a bevel gear arranged to mesh with said 50 pinions, said gear being provided with a set of teeth covering a portion of its circumference only, certain of said teeth being of a length to mesh with either of said pinions and the remainder being of a length to mesh 55 with only one of said pinions, said pinions being so arranged that only one of them is in mesh with said gear at one time.

In testimony whereof I affix my signature in presence of two witnesses.

HARRY M. NEER.
